CLAIM

The ornamental design for a nozzle for inflating a hypothermia blanket, as shown and described.

DESCRIPTION

FIG. 1 is a perspective view of a nozzle for inflating a hypothermia blanket showing my new design; FIG. 2 is a top elevational view thereof, with it being understood that the bottom elevational side view is a mirror image thereof;

FIG. 3 is a left side elevational view thereof, with it being understood that the right side elevational view is a mirror image thereof;

FIG. 4 is a front end plan view thereof; and,

FIG. 5 is a rear end plan view thereof.

FIG. 1

FIG. 2

FIG. 3

FIG. 4

FIG. 5
